UNITED STATES PATENT OFFICE.

EDWARD D. McCHEY, OF SEATTLE, WASHINGTON.

SHIRT-PROTECTOR.

1,110,701.

Specification of Letters Patent. Patented Sept. 15, 1914.

Application filed February 16, 1914. Serial No. 819,027.

To all whom it may concern:

Be it known that I, EDWARD D. McCHEY, a citizen of the United States, residing at Seattle, in the county of King and State of Washington, have invented certain new and useful Improvements in Shirt-Protectors, of which the following is a specification, reference being had to the accompanying drawings.

10 This invention relates to new and useful improvements in shirt protectors and more particularly to a protector such as are used by laundries and the primary object of the invention is to provide a device of this character which will retain the shirt in its folded position and, at the same time, will protect the same from dirt, dust, and the like.

20 A still further object of the invention resides in providing a protector designed in the form of a folder constructed from a single sheet of material.

25 A still further object of the invention resides in providing a device which is simple and durable in construction, inexpensive to manufacture and one which will be very efficient and useful in operation.

30 With these and other objects in view, the invention consists in the novel features of construction, combination and arrangement 35 of parts as will be hereinafter fully described and claimed.

In the accompanying drawings forming a part of this application, Figure 1 is a plan view of the blank in its outspread position. Fig. 2 is an edge view thereof. Fig. 3 is a rear elevation of the folder in its folded position with the tab for introduction into the neck-band of the shirt extended. Fig. 4 is a longitudinal section taken on the line 40 4-4, of Fig. 3. Fig. 5 is a fragmentary plan view of the folder in its semi-folded condition, showing the position of the upper and lower flaps thereon. Fig. 6 is a perspective view of the folder in a semi-folded 45 condition. Fig. 7 is a detail plan view of the means of engagement of the one side flap with the other side flap. Fig. 8 is a front elevation of the folder completely folded and having a shirt inclosed therein; 50 and Fig. 9 is a detail perspective view showing the primary interlocking means between the side flaps which, together form the rear wall section of the device.

55 In describing my invention, I shall refer to the drawing in which similar reference

characters designate corresponding parts throughout the several views and in which—

1 indicates a sheet or blank formed of heavy paper or pasteboard, the same being composed of a central or front wall 2 having the side flaps 3 and 4 formed, respectively on the side edges thereof which, together, are adapted to form a rear wall for the folder. These side flaps 3 and 4 are adapted to be bent along the dotted lines 5, 60 which lines are formed in the device by scoring or otherwise indenting the sheet. Also formed on the lower edge of the front wall 2, is a bottom flap 6 which is adapted to be bent upwardly against the rear face of the 70 front wall 2 along the line 7, which is also formed by scoring or indenting the sheet. An additional tongue or flap 8 is formed on the upper edge of the front wall 2, the same being adapted to be bent inwardly against 75 the rear face of the wall 2, along the dotted line 9. As stated, the flaps 3 and 4 are adapted to be folded inwardly along the lines 5, to form the rear wall flaps of the 80 folder, the same being adapted to overlap one another, and I have provided an improved means for securing these flaps 3 and 4 together. To this end, a vertical longitudinal slot 10 is formed about centrally 85 of the flap 4, while the flap 3 is slit or slotted longitudinally at 11. This slit or slot 10 terminates in triangularly-shaped openings 12, thus providing a pair of tabs or tongues 13 and 14. In folding the device, the flap 3 is folded over the flap 4 and the 90 free edge of the latter is received through the slot 10 in the section 4 and flaps 3 and 4 95 are then securely locked in their overlapping and folded positions. It will be understood that prior to the folding of the flaps 3 and 4 over one another, the bottom flap 6 is folded inwardly against the rear face of the 100 front wall 2. The shirt being placed face forward, against the rear face of the wall 2, the bottom flap 6 is folded inwardly against the rear face of the shirt and the flaps 3 and 4 then properly folded thereover and 105 interlocked one with the other through the medium of the means just described.

The top flap 8 is folded over the neck-band of the shirt and under the overlapping flaps 3 and 4, and I have provided a means in con- 110

nection with the top flap to admit a portion of the neck of the shirt to be exposed, whereby the mark therein may be readily observed. To this end, a pair of spaced longitudinal slits or slots 15 are provided which extend partially through the upper portion of the wall 2 and partially through the top flap 8. These slits or slots 15 are connected by a horizontal or transverse slit 16, which 5 extends through the top flap 8, and thus when latter is folded inwardly over the upper portion of the shirt, and auxiliary top tab 17 remains, which is foldable inwardly, with respect to the wall 2, along a line 18. 10 This line, as in the other instances, may be scored or otherwise indented in the sheet or blank. This tab 17 is adapted to be folded inwardly into the neck of the shirt and under the bosom thereof, thus exposing a portion 15 of the neck-band and the back of the shirt, adjacent the neck-band, to admit the mark therein to be readily observed. In bending the tab 17 to its effective position, the same is preferably folded along the 20 transverse lines 19.

In order to securely lock the folder in position, after being properly folded over the shirt, the diagonal slits 20 are provided in the flap 4 which are adapted to receive the 25 corners of the overlapping flap 3. When these corners are introduced through the slits 20 and the above described locking means properly engaged, the flaps 3 and 4 will be securely locked together to form the 30 rear wall of the folder.

From the foregoing description of the construction of my improved device, the manner of applying the same to use will be readily understood and it will be seen that I have 35 provided an improved shirt protector which

is of the folder design and which will positively protect the shirt under all conditions. It will also be seen that the device is simple and durable in construction, inexpensive to manufacture and one which will be very 45 efficient and useful in operation.

While I have particularly described the elements best adapted to perform the functions set forth, it is obvious that various changes in form, proportion and in the 50 minor details of construction may be resorted to without departing from the spirit or sacrificing any of the principles of the invention.

Having thus described this invention, what 55 I claim is:

A folder of the character described comprising a front wall, top and bottom flaps formed thereon and foldable inwardly against the rear face thereof, an outwardly disposed tab struck from an end portion of the front wall and the adjacent end flap and foldable inwardly against the rear face of the front wall, said line of fold being intermediate of the length of the tab, side flaps 65 formed on the sides of the front wall and foldable inwardly in overlapping relation to one another to provide a rear wall, one of the side flaps being provided with a slot and with terminal oppositely inclined slits and 70 the other being slotted and cut-away to form a pair of tabs for engagement with the slot, the slits being engaged by the free corners of the latter tabs.

In testimony whereof I hereunto affix my 75 signature in the presence of two witnesses.

EDWARD D. McCAYEY.
